MECHANISM FOR TRANSFORMING ONE
FORM OF MOVEMENT INTO ANOTHER,
MORE PARTICULARLY FOR USE IN
STENCIL PRINTING MACHINESJames Edward Freeborn, Broxbourne, England,
assignor to Screen Printing Machinery Limited, London, EnglandApplication May 29, 1951, Serial No. 228,832

13 Claims. (Cl. 101—123)

1

The need sometimes arises for transforming a cyclical movement of a driving member into an oscillatory movement of a driven member, which latter movement is intermittent in the sense that it does not continuously follow the movement of the driving member but is interrupted periodically so that the driven member is stopped at intervals during the movement of the driving member.

An example of a machine in which the need for such a mechanism has been encountered is a stencil printing machine of the kind having a screen frame carrier which is provided with an inking carriage, mounted for movement along the screen. The screen frame carrier is movably mounted above a printing table and is arranged to be lowered onto the table when a printing stroke is to be made, after which it is raised from the table to allow of the removal of the printed sheet and of the feeding into position on the table of a fresh sheet and is then again lowered for the next printing operation.

With one form of machine, an example of which is described in my prior application Serial No. 184,942 filed September 6, 1950, the inking carriage is arranged to make a single printing stroke along the screen frame in one direction to effect a printing operation, after which the carriage remains stationary at one end of the frame during the time that the latter is raised and lowered and a fresh sheet is fed into position. After the screen has been lowered onto this fresh sheet the inking carriage makes a return printing stroke in the opposite direction.

The raising and lowering of the screen frame is preferably effected by mechanism operated from a continuously rotating shaft, such as for example by the cam mechanism described in the aforesaid application. It is one of the objects of the present invention to provide mechanism which is adapted to be operated in synchronism with the operation of such a shaft so as to produce the required printing stroke of the inking carriage in alternate directions, which strokes are correctly synchronised with the raising and lowering of the screen frame carrier and have the required intervals or "dwell" between them corresponding to the times when the screen carrier is not in its printing position.

In order to reduce the power required to operate the inking carriage and to reduce the stresses produced in the mechanism, while at the same time maintaining an adequate speed of operation, it is preferred that the operation of the inking carriage should be harmonic in nature in that the

2

carriage is caused to accelerate progressively from rest to reach its maximum speed at an intermediate point in its travel, after which it progressively decelerates until it reaches the end of its stroke. It is one of the objects of this invention to provide mechanism for achieving this.

Although the movement-converting mechanism which is to be described is particularly applicable to the operation of the inking carriage in a stencil printing machine its use is not limited to such machines. It can be applied to machines of other types in which a similar action is required and it is, accordingly, a more general object of the present invention to provide mechanism for converting a cyclical movement of any driving member, which movement may be rotary or oscillatory in character, into an intermittent oscillatory movement of a driven member.

According to the invention, in one aspect thereof, mechanism is provided for converting a cyclical movement of a driving member into an intermittent oscillatory movement of a driven member, comprising an actuating element which is reciprocated by the driving member and a selector member, which is operatively coupled to the driven member so as to drive the latter, wherein the selector member is provided with a pair of abutment members, each movable between an operative and an inoperative position, one of which members is adapted when in its operative position to be engaged by the actuating element when the latter is travelling in one direction so as to operate the selector member in that direction and the other of which elements is adapted when in its operative position to be engaged by the actuating element when the latter is travelling in the reverse direction so as to operate the selector member in that reverse direction, and wherein means are provided operated from the driving member for moving the abutment members between their operative and inoperative positions such that the selector member is operated during selected strokes only of the actuating element.

In the case of the application of the invention to a stencil printing machine there is provided, according to a further aspect of this invention, a stencil printing machine comprising a frame structure carrying a printing table, a screen frame carrier movably mounted on said structure for movement towards and away from the printing table, an inking carriage reciprocable along the screen frame carrier, a rotary driving shaft, means operated by the driving shaft for

raising and lowering the screen frame carrier and mechanism operated from the shaft for reciprocating the inking carriage along the frame carrier, wherein the said mechanism comprises an actuating element which is reciprocated by the rotation of the driving shaft, a reciprocable selector member and means transmitting the movements of the selector member to the inking carriage, the selector member being provided with a pair of abutment members, each movable between an operative and an inoperative position, one of which members is adapted when in its operative position to be engaged by the actuating element when the latter is travelling in one direction so as to operate the selector member in that direction and the other of which members is adapted when in its operative position to be engaged by the actuating element when the latter is travelling in the reverse direction so as to operate the selector member in that reverse direction, and means being provided operated from the driving shaft for moving the abutment members between their operative and inoperative positions such that the selector member is operated during selected strokes only of the actuating element, whereby the inking carriage is caused to make single printing strokes in alternate directions during the times when the screen frame carrier is in its printing position adjacent the table.

The movement of the selector members produced by the mechanisms referred to is reciprocating and generally linear in character and its amount is limited by structural considerations. It is yet another object of this invention to provide mechanism for converting the linear movement of the selector member into an amplified rotational movement of a rotary driven member, the extent of which movement may amount if necessary to several complete revolutions.

In some applications of the invention this rotary movement may be employed directly without further modification, but in the case of a stencil printing machine it is used to drive the inking carriage which is caused to reciprocate through a distance which may be substantially greater than the stroke of the selector member.

For the better understanding of the invention the application of the same to the driving of the inking carriage of a stencil printing machine will now be described. Reference will be had to the accompanying drawings, in which:

Figure 1 is a general side view of a stencil printing machine exemplifying the invention;

Figure 2 is a detail view showing part of the mechanism for driving the inking carriage;

Figure 3 is a detail view showing parts of the mechanism of Figure 2 in the positions occupied at a later stage in the operation of the machine;

Figure 4 is a view similar to Figure 2 but showing a still later stage in the operation.

Referring first to Figure 1, which is to some extent diagrammatic in character, the machine comprises a frame structure 1 of any suitable construction which supports a printing table 2, a feed table 3 and a delivery table 4. The delivery table 4 forms in effect a continuation of the surface of the printing table 2, as does the front portion and one side of the feed table 3. The main part 5 of the feed table is, however, arranged to be adjustable in height, part of the mechanism for raising and lowering it being indicated at 6 in Figure 1. In use a stack of sheets to be printed is placed on the part 5 of the feed table, which is progressively raised as printing 75 required.

proceeds so that the top sheet is always level with or a little above the level of the printing table.

Feed and delivery mechanism which may be of the kind described in the aforesaid prior application is provided for drawing a sheet from the feed table 3 into the printing position on the printing table 2 and for delivering this sheet, after printing, on to the delivery table 4.

A chain 7, which is driven through mechanism indicated diagrammatically at 8, forms part of the paper feed and delivery apparatus, which latter will not, however, be described further since it forms no part of the present invention.

Suction mechanism of the conventional type may be provided for holding the sheets down on the printing table during printing and, if desired, during the first part of the upward movement of the screen away from the table.

The stencil screen to be used is fitted in a suitable frame (not shown) which is mounted in a screen frame carrier indicated generally at 9. Slidably mounted on suitable rails or guides forming part of this carrier 9 is an inking carriage 10 which is arranged to be operated by means of a pair of chains 11 which are provided at opposite sides of the frame carrier and each of which is attached at its ends to the inking carriage.

The carriage 10 is provided with a pair of squeegees (not shown) either one of which is arranged to be brought into engagement with the stencil screen according to the direction of movement of the carriage. Automatic mechanism of any suitable type is provided for automatically raising one squeegee and lowering the other when the carriage is at or near the limits of its movement in opposite directions. Parts of this mechanism are shown at 12, 13 and 14 but no further description of it will be given since it forms no part of the present invention.

Each of the chains 11 is trained about sprockets 15 and 16 mounted at opposite ends of the frame carrier 9. The sprockets 15 are idler sprockets but the two sprockets 16 at the other end of the frame carrier are secured to a shaft 17 which shaft extends across the carrier. This shaft 17 is arranged to be driven from a short shaft 18 by means of a chain 19 which is trained about sprockets mounted on the outer ends of these shafts. The shaft 18 itself forms a pivotal connection between the frame carrier 9 and a bearing bracket mounted on the frame structure 1 of the machine at one side of the latter, while at the other side of a machine a similar pivotal mounting for the carrier 9 is provided by means of another shaft or pin which is similar to the shaft 18 but which forms no part of the driving mechanism.

The mechanism for raising and lowering the frame carriers 9 will now be described. This mechanism comprises a main cam shaft 20 which is journaled in suitable bearings provided in the frame structure 1 and which is continuously driven from the main driving motor 20a of the machine through a reduction gearbox (indicated generally at 21) having an input shaft 22 which drives a main output or driving shaft 23 through a two stage reduction gearing.

Mounted on one end of the shaft 22 is a pulley 24 which is driven by means of a belt 25 from a pulley 26 mounted on the shaft of the motor 20a. It is preferred for the pulleys 24 and 26 to be of the stepped or multi-groove type so that the speed of working of the machine can be adjusted as required.

One end of the driving shaft 23 carries a sprocket 27 from which the drive is transmitted to the cam shaft 20 by means of a chain 28 which passes round a sprocket 29 mounted on the cam shaft. The sizes of the sprockets 27 and 29 are such as to provide a 3:2 speed reduction between the driving shaft 23 and the cam shaft 20.

At each of its ends the cam shaft 20 carries a cam 30, which cams engage rollers 31 which are mounted on operating arms 32 provided at opposite sides of the machine. Each arm 32 is pivoted at one end to a bracket 33 mounted on the side of the machine, while its other end is connected by means of a link 34 with a lifting rod 35 which is slidably mounted in guides 36 and 37.

Each of the rods 35 is provided at its upper end with a roller 38 bearing against a plate 39 mounted on the underside of the frame carrier 9. Consequently as the cam shaft 20 rotates the frame carrier is raised and lowered by the action of the cams 30.

The speed with which the frame carrier 9 can be raised is limited not only by the weight and inertia of the parts concerned, but also by the fact that during the raising operation the printed sheet has to be separated with a peeling action from the underside of the screen. The lowering of the frame carrier can, however, be effected more rapidly, and the cams 30 may be appropriately shaped to give this result, while allowing the frame carrier to remain in its lower position for the period required for the printing stroke.

Thus, to give one example, the raising of the carrier 9 may occupy 120° of the rotation of the cam shaft 20, after which the carrier is held in its raised position for a further 60° of this rotation in order to provide adequate time for the removal of the printed sheet and for the feeding of a fresh sheet on to the printing table. The next 60° of the rotation of the cam shaft effects the lowering of the carrier, after which the latter is allowed to remain in its lowered position for the remaining 120° of the rotation of the shaft 20, during which time the carriage 10 effects a printing stroke.

It is important to note that the cam 30 should be so shaped that the raising and lowering movements of the carrier 9 are harmonic in character in that the carrier is made to accelerate progressively until it reaches its maximum speed of movement, after which it is progressively decelerated as it nears the end of its travel. This greatly reduces the shocks and strains which are produced in the mechanism.

The mechanism for operating the inking carriage will now be described.

This mechanism comprises a crank 40 (Figures 2 to 4) which is mounted on the driving shaft 23 of the gear box 21 on the side of the latter opposite the sprocket 27. This crank 40 is connected at 41 to a connecting rod 42 which is provided at its other end with an actuating roller 43. With the parts in the positions shown in Figures 2 and 4 this roller 43 rests on a member 44 which is attached to a pair of parallel, substantially-horizontal selector plates 45. These plates are pivotally connected at 46 and 47 to two pivot arms 48 and 49 which are in turn pivoted at 50 and 51 to the frame of the machine. In this way the selector plates 45 are supported for limited reciprocating movement along an arcuate path between the position shown in Figures 2 and 3 and that shown in Figure 4. The amount of this movement is limited by means of adjustable stops

52 and 53 which are adapted to engage a part of the frame structure of the machine, such as the lower edge 54 of an opening in one of the side plates of this structure. In the construction shown the stops 52 and 53 are constituted by screws which are mounted in a bracket 55 on the pivot arm 48 and which are provided with lock nuts 56 and 57.

Mounted between the selector plates 45 are two abutment members 58 and 59 which are pivoted to the plates 45 at 60 and 61 respectively. The member 58 is movable between a lower inoperative position as shown in Figure 2 and an upper operative position which is shown in Figures 3 and 4, while the member 59 is similarly movable between the lower, inoperative position of Figures 3 and 4 and an upper operative position which is shown in Figure 2.

When one of the abutment members is in its upper operative position movement of the connecting rod towards the member will cause the roller 43 to engage the abutment member and thereby to move the selector plates from one limit position to the other. When, however, one of the abutment members is in its lower position movement of the connecting rod in the direction of that member will merely cause the roller 43 to run along the upper surface of the member and the selector plates will not be operated.

30 The abutment members 58 and 59 are provided with spring-urged plungers 62 and 63 (Figure 2) respectively, the ends of which plungers bear resiliently against the sides of the member 44 and are adapted when the abutment members 35 are in their upper positions to engage in V-shaped notches 64 and 65, which notches limit the upward movement of the members 58 and 59 and tend to retain these members in their upper positions until they are moved from them by the 40 mechanism now to be described.

This mechanism comprises a link 66 which is pivotally connected at its ends to upstanding stop arms 67 and 68, which latter are rigidly mounted on the abutment members 58 and 59 respectively. The length of the link 66 is such that when one abutment member is moved to its lower position, the other abutment member is raised to its upper position, and vice versa. The positions of the stop arms 67 and 68 are such that when the roller 43, running along the upper surface of one of the abutment members, nears the end of its stroke it engages the corresponding stop arm and rocks the latter so as to raise this abutment member while at the same time lowering the other member (see Figure 3).

55 In order to ensure correct operation of the selector plates a rod 69 carrying a pair of compression springs 70 and 71 is pivotally connected at 72 to the member 44, while its lower end passes slidably through a block 73 which is pivoted at 74 to the frame 1. The action of the springs 70 and 71 causes the rod 69 to urge the selector plates 45 to the right or to the left, depending on whether they are on one side or the other of their central position.

65 The operation of the above selector mechanism will be described in due course in conjunction with the remainder of the drive to the inking carriage.

70 The reciprocatory movements imparted to the selector plates 45 by the crank 40 and the connecting rod 42 are converted into rotational movement in alternating directions by means of an epicyclic mechanism which is indicated generally at 75. This mechanism comprises a sun-

wheel 16 which is secured to a shaft 17 journalled in bearings provided on the frame of the machine. Freely rotatable on this shaft 17 are an internally toothed annulus 18 and a planet carrier 19. This planet carrier carries a number of planet wheels 20 which mesh with the sun-wheel 16 and with the annulus 18.

Two link arms 21 and 22 are provided, pivoted at 23 to the selector plates 25. The arm 21 is connected at 23 to the annulus 18 at a point above the axis of the shaft 17, while the arm 22 is connected at 24 to an extension of the planet carrier 19. As a result of this arrangement, when the selector plates 25 are moved to the left the link 21 rotates the annulus 18 in an anti-clockwise direction, while the link 22 rotates the planet carrier 19 in a clockwise direction. These rotations of the annulus and planet carrier have a cumulative action and impart to the sunwheel 16 a considerably amplified rotation in a clockwise direction. The amount of this rotation may amount to several revolutions, depending on the relative sizes of the gears involved.

The shaft 17 is connected to the shaft 18 by means of a chain 26 which is trained about sprockets mounted on these shafts. A tensioning sprocket 27 may be provided for adjusting the tension of the chain if necessary.

It will be seen that the effect of the epicyclic mechanism just described will be to convert the relatively short, reciprocatory movements of the selector plates 25 into amplified movements of the inking carriage 10 which is thereby caused to make the required printing strokes as will be described. It is preferred to make the sprockets carrying the chain 26 accessible and readily interchangeable so that they can be changed when required in order to give a change of ratio in the drive to the carriage. This is very advantageous since it enables the printing stroke to be limited to the length of the particular sheet being used, while in multi-colour printing, in which some of the colours may be grouped in different small areas of a large print, the stroke can be limited to cover only the particular area concerned. The use of the maximum stroke under such conditions would be wasteful in ink as well as in the silk screen material, it would increase the amount of the preparatory work necessary in setting up the machine and would restrict the speed of printing of a small sheet or part of a sheet to that required for printing a full-sized sheet.

The operation of the screen raising and carriage drive mechanism will now be described. It will be assumed that the parts are in the positions shown in Figure 2 and that a printing stroke has just been completed so that the frame carrier 9 is about to be lifted by the action of the cams 30. During the time that the cam shaft 20 is turning through 120° to raise the frame carrier to the start of its dwell at the point of maximum lift, the crank 40 turns through 180° owing to the 3:2 gearing between the shafts 23 and 20. Owing to the abutment member 58 being lowered at this time the roller 43 during this movement of the crank runs up the member 58 until, as it nears the end of its stroke, it engages the stop rod 67 and operates the latter to raise the member 58 and at the same time to lower the member 59, as is shown in Figure 3. The selector plates 25 are not operated during this movement of the roller and thus no movement is transmitted to the inking carriage.

During the next 130° rotation of the crank 40 the roller 43 runs back down the left-hand abutment member until it drops off the end of the latter on to the member 44, as is indicated in dot-and-dash lines in Figure 3. During this stroke also no movement is imparted to the selector plates and to the inking carriage.

This last 180° movement of the crank 40 corresponds to a 120° rotation of the cam shaft 20. During the first half of this rotation the frame carrier 9 is held in its upper position and during the second half thereof it is allowed to descend into contact with a work sheet on the table, ready for printing. In its lower position the frame carrier 9 engages fixed stops 67 mounted on the brackets 30.

During the next half turn of the crank 40 (which corresponds to a 120° rotation of the cam shaft 20 during which the frame carrier 9 remains lowered) the tracking roller 43 engages the end face of the abutment member 58 (which is now raised) and thereby moves the selector plates 25 through one complete stroke from right to left, thereby bringing them to the position shown in Figure 4. This movement is transmitted through the mechanism 75 to the inking carriage 10 which is thereby caused to make a printing stroke in one direction along the screen.

During the next half-turn of the crank 40 the roller 43 runs up the abutment member 59, without operating the selector plates, until it engages the stop rod 67 to reverse the positions of the abutment members. During this time the cam shaft 20 turns through the first 120° of its next complete rotation, thus again raising the frame carrier 9 with the stencil frame. The previously-described sequence of operations is thus repeated (but in the reverse directions) with the roller 43 running back along the member 59 until it drops on to the member 44, after which during the next movement of the connecting rod 42 to the right the roller 43 engages the end of this abutment member and moves the selector plates to the right. Thus in this second printing operation the inking carriage 10 makes a printing stroke in the reverse direction.

Although the movement-conversion or "selector" mechanism of the invention, which is centered about the selector plates 25, is particularly applicable to the driving of the inking carriage of a screen printing machine and has been described with reference to such a machine, the invention is not limited thereto. This mechanism can be employed in other cases in which a similar conversion of one form of movement into another is required. It may be employed in conjunction with a speed-multiplying mechanism, such as is represented by the epicyclic mechanism 75, or such mechanism may be omitted if it is only desired to obtain a reciprocatory or limited angular movement of the member to be driven by the mechanism.

I claim:

1. Mechanism for converting a cyclical movement of a driving member into an intermittent oscillatory movement of a driven member comprising an actuating element which is reciprocated by the driving member and a selector member which is operatively coupled to the driven member so as to drive the latter, wherein the selector member is provided with a pair of abutment members, each movable between an operative and an inoperative position, one of which members is adapted when in its operative position to be engaged by the actuating element

when the latter is travelling in one direction so as to operate the selector member in that direction and the other of which members is adapted when in its operative position to be engaged by the actuating element when the latter is travelling in the reverse direction so as to operate the selector member in that reverse direction, and wherein means are provided operated from the driving member for moving the abutment members between their operative and inoperative positions such that the selector member is operated during selected strokes only of the actuating element.

2. Mechanism as claimed in claim 1, wherein the abutment members are operatively coupled together such that when one member is moved to its operative position the other is moved to its inoperative position.

3. Mechanism as claimed in claim 2, wherein each abutment member is provided with a stop element which is adapted to be engaged by the actuating element and to be operated by it so as to move the said abutment member to its operative position while the actuating element is making an inoperative stroke without having engaged that abutment member.

4. Mechanism as claimed in claim 1, wherein the abutment members are constituted by a pair of pivoted levers having their free ends directed towards each other in positions to be engaged by the actuating element when the appropriate lever is in its operative position.

level is in its operative position.

5. Mechanism as claimed in claim 1, wherein the actuating element is arranged to be reciprocated by means of a connecting rod driven from a rotating driving shaft.

6. Mechanism as claimed in claim 5, wherein the actuating element engages each of the abutment members to operate the selector member once in every three strokes of the actuating element in the appropriate direction and wherein the driving shaft is connected with a control shaft through a 3:2 speed reduction gearing such that the selector member is given a single stroke in one direction during each complete rotation of the control shaft.

7. Mechanism as claimed in claim 1, wherein the reciprocatory movements of the selector member are transmitted to a rotary driven member by means including an epicyclic gear having three elements, two of which elements are connected with the selector member so as to be turned by the latter in opposite directions such that the movements of these elements produce a cumulative movement of the third element, which latter element is connected to the driven member.

8. A stencil printing machine comprising a frame structure carrying a printing table, a screen frame carrier movably mounted on said structure for movement towards and away from the printing table, an inking carriage reciprocable along the screen frame carrier, a rotary driving shaft, means operated by the driving shaft for raising and lowering the screen frame carrier and mechanism operated from the shaft for reciprocating the inking carriage along the frame carrier, wherein the said mechanism comprises an actuating element which is reciprocated by the rotation of the driving shaft, a reciprocable selector member and means transmitting the movements of the selector member to the inking carriage, the selector member being provided with a pair of abutment members, each movable between an operative and an inoperative

position, one of which members is adapted when in its operative position to be engaged by the actuating element when the latter is travelling in one direction so as to operate the selector

- 5 member in that direction and the other of which members is adapted when in its operative position to be engaged by the actuating element when the latter is travelling in the reverse direction so as to operate the selector member in

10 that reverse direction and means being provided operated from the driving shaft for moving the abutment members between their operative and inoperative positions such that the selector member is operated during selected strokes only of

15 the actuating element, whereby the inking carriage is caused to make single printing strokes in alternate directions during the times when the screen frame carrier is in its printing position adjacent the table.

20 9. A stencil printing machine as claimed in claim 8, wherein the abutment members are operatively coupled together such that when one member is moved to its operative position the other is moved to its inoperative position.

25 10. A stencil printing machine as claimed in claim 9, wherein each abutment member is provided with a stop element which is adapted to be engaged by the actuating element and to be operated by it so as to move the said abutment member to its operative position while the actuating element is making an inoperative stroke without having engaged that abutment member.

30 11. A stencil printing machine as claimed in claim 8, wherein the abutment members are constituted by a pair of pivoted levers having their free ends directed towards each other in positions to be engaged by the actuating element when the appropriate lever is in its operative position.

35 40 12. A stencil printing machine as claimed in claim 8, wherein the frame carrier is operated from a cam shift so as to be raised and lowered once during each complete rotation thereof, wherein the actuating element engages each of the abutment members to operate the selector member once in every three strokes of the actuating element in the appropriate direction and wherein the driving shaft is connected with the cam shift through a 3:2 speed reduction gearing such that the selector member is given a single stroke in one direction during each complete rotation of the cam shaft.

45 50 55 60 13. A stencil printing machine as claimed in claim 8, wherein the means transmitting the movements of the selector member to the inking carriage include an epicyclic gear having three elements, two of which elements are connected with the selector member so as to be turned by the latter in opposite directions such that the movements of these elements produce a cumulative movement of the third element, which latter element is connected to the inking carriage.
